DESIGN FOR A SCALE

Alexander J. Kurk, Brooklyn, and Henrik Hoyer,
New York, N. Y., assignors to The Jacobs Bros.
Co., Inc., Brooklyn, N. Y., a corporation of New
York

Application June 3, 1936, Serial No. 62,993

Term of patent 7 years

To all whom it may concern:

Be it known that we, Alexander J. Kurk and Henrik Hoyer, both citizens of the United States, and residing respectively at Brooklyn, county of Kings and State of New York, and city, county, and State of New York, have invented a new, original, and ornamental Design for a Scale, of which the following is a specification, reference being had to the accompanying drawing forming a part thereof, wherein:

Fig. 1 is a perspective view of a scale showing our new design;

Fig. 2 is a plan view thereof; and—

Fig. 3 is a side elevation.

We claim:

The ornamental design for a scale, as shown.

ALEXANDER J. KURK.
HENRIK HOYER.
